UNITED STATES PATENT OFFICE

ANTONIO FABBRO, OF TAMPA, FLORIDA

DESIGN FOR A BENCH OR SIMILAR ARTICLE

Application filed December 19, 1929. Serial No. 33,859. Term of patent 14 years.

To all whom it may concern:

Be it known that I, ANTONIO FABBRO, citizen of the United States, residing at Tampa, in the county of Hillsborough and State of Florida, have invented a new, original, and ornamental Design for Bench or Similar Article, as shown in the accompanying drawing and described in the following specification.

In the accompanying drawings—

Figure 1 is a perspective view showing my design for a bench or similar article; and

What I claim is:

The ornamental design for a bench or similar article, as shown.

ANTONIO FABBRO.
